ROOF VENTILATOR

Harold B. Hawes, Fairfield, Conn.

Application December 4, 1944, Serial No. 566,548

6 Claims. (Cl. 98—42)

1

The present invention relates to a roof ventilator, and particularly a ridge type ventilator for mounting along the ridge of the roof to form a structural part thereof, an object of the invention being to provide a ventilator of such form and appearance as to harmoniously combine with the architectural design of the building, while at the same time providing an effectual ventilator for obtaining complete and uniform ventilation of the interior of the building.

It is particularly proposed to provide a ventilator structure wherein a series of longitudinally spaced vertical pipe members is provided, these members projecting above the mounting base of the ventilator and being surmounted by a continuous cap member, disposed over the open ends of the pipe members and extended inwardly and downwardly at each side, with its lower edges terminating in upwardly spaced relation to the mounting base.

The arrangement is such that air flow spaces are provided below the cap member which extend horizontally across the ventilator between the pipe members, the entrances to these spaces at each side being defined by the convergent surfaces of the cap member and the base of the ventilator, and the spaces themselves being defined by the convergent surfaces of the adjacent pipe members, so that a substantial velocity increase is induced in the horizontal flow of air through the ventilator, and an effectual aspirating effect is produced in the cap member to forcibly draw streams of air upwardly through the pipe members. This aspirating effect, combined with the upward flow of warm air naturally induced in the pipe members, results in a uniform and rapid out-flow of air through the ventilator.

A further object is to provide a ventilator which will effectually seal the roof against the entrance of rain, snow, and the like, while at the same time permitting the uninterrupted horizontal flow of air through the air flow spaces between the pipe members.

A further object is to provide damper means for closing or controlling the opening of the ventilator pipe members, such damper means being out of the path of the horizontal flow of air currents through the spaces between the pipe members.

With the above and other objects in view, an embodiment of the invention is shown in the accompanying drawings, and this embodiment will be hereinafter more fully described with reference thereto, and the invention will be finally pointed out in the claims.

In the drawings—

Fig. 1 is a side elevation, partially in vertical section, of one end of the ridge structure of a roof provided with a ventilator according to the

illustrated exemplary embodiment of the invention.

Fig. 2 is a vertical sectional view, taken along the line 2—2 of Fig. 1.

Fig. 3 is a vertical sectional view, on an enlarged scale, taken along the line 3—3 of Fig. 1.

Similar reference characters indicate corresponding parts throughout the several figures of the drawings.

10 Referring to the drawing, the roof structure comprises a ridge beam 10, rafters 11, nailing strips 12 and a roof covering 13, the latter being of any suitable type, as for instance shingles, slate, and the like. The upper nailing strips 12 and the upper edges of the roof covering 13 are disposed in spaced relation to the ridge center of the roof, so as to provide a substantial air space at each side of and above the ridge beam 10. To the upper marginal portions of the roof covering there are secured curb strips 14 for the purpose of attaching the ventilator unit, according to the invention.

The ventilator unit comprises a base 15 formed of sheet metal, and bent along longitudinal lines to provide a central longitudinally extending horizontal portion and inclined portions at each side parallel to the inclined sides of the roof, these side portions being provided at their lower edges with attaching flanges 16 engaged over the lower edges of the curb strips 14 and secured thereto by nails 17. The horizontal central portion of the ventilator base is provided with a series of longitudinally spaced circular openings having upwardly bent rim flanges 18, and in each of which is secured a pipe member 19. Each of these pipe members is provided at its lower end with an outwardly extending flange 20 engaging the under side of the ventilator base and with external screw threads 21 extending above the base, a clamping nut 22 being screwed thereon in clamping relation with the upper side of the base. This clamping nut is provided at its under side with a tapered recess 23 in which is engaged the rim flange 18, tightening of the nut causing the flange to be tightly compressed about the pipe member. While this provides a tight weather seal, a suitable weather sealing mastic material 24 is preferably placed within the recess 23 about the rim flange 18.

55 In practice, the pipe members may be approximately 2½ to 3 inches in diameter and spaced apart a distance of 3 to 4 inches, and they preferably extend the full length of the ventilator. At suitable intervals yoke members 25 are secured to certain of the pipe members by means of screws 26 at each side, these yoke members being of circular form and being attached at a substantial distance below the upper ends of the pipe members, for the purpose of retaining upon the pipe members the cap member 27. This cap

member is of cylindrical form, open at its under side and extends the full length of the ventilator, being mounted within the yoke members so that its lower edges abut the sides of the pipe members, and are in upwardly spaced parallel relation to the ventilator base. At each end the cap member is closed by a flanged cover 28, welded or otherwise suitably secured in place.

The pipe members are preferably provided at their upper ends with a flanged screen insert 29 for the purpose of preventing entrance of insects, dirt, etc., through the pipe members.

Within the cap member there is provided a damper 30 having at its under side a suitable sealing layer 31 for engaging the upper ends of the pipe members, this sealing layer being secured by the folded flanges 32 extending along the longitudinal edges of the damper. For the purpose of raising and lowering the damper, to close the pipe members or to adjust the open space above them, it is supported upon a series of screw posts 32 mounted in certain of the pipe members spaced at suitable distances apart, these posts being each connected to the damper by a swivel pin connection 33 and provided with a high pitch thread 34 engaged in an internally threaded bushing 35 secured in the pipe member by means of a set screw 36. At its lower end the screw post is provided with a lever arm 37, pivotally connected at 38 to a horizontal draw rod 39, provided with a handle 40 extending downwardly at one side of the ridge beam 10. Longitudinal movement of the draw rod imparts swinging movement to the lever arms 37 of the several screw posts causing them to be simultaneously rotated and moving the damper between the raised open position, shown in full lines in Fig. 1, and the lowered closed position, shown in dot-and-dash lines in Fig. 1. Partial movement of the draw rod between its extreme positions will move the damper to any desired position of adjustment.

The arrangement of the cap member 27 in spaced relation above the base 15 of the ventilator provides a horizontal air flow space through the ventilator, the entrances to this space at each side being defined by the convex outer surface of the cap member and the downwardly inclined sides of the base member, so that these entrances converge and result in an accelerated flow of air through the ventilator. This flow of air is along air flow paths between the pipe members 19, and the external opposed cylindrical surfaces of the adjacent pipe members are such that the air flow spaces between them converge from each side to the center. Hence, there is an additional accelerating effect as the air flows between the pipes. Thus with very little air current there is a substantially accelerated flow of air through the ventilator causing a suction or aspirating effect in the cap member of a relatively high order. This in turn draws streams of air upwardly through the pipe members, and in combination with the natural upward flow of the higher temperature air within the roof enclosure results in a rapid and uniform ventilation of the building. The cap member 27 protects the open ends of the pipe members against the entrance of vertically falling rain as well as diagonally or horizontally driven wind swept rain, the latter being carried through the air flow spaces below the upper ends of the pipe members.

I have illustrated and described preferred and satisfactory embodiment of the invention, but it will be understood that changes may be made

therein, within the spirit and scope thereof, as defined in the appended claims.

Having thus described my invention, what I claim and desire to secure by Letters Patent is:

5 1. A ventilator, comprising a base adapted to be mounted over an elongated opening and having a series of longitudinally spaced upwardly extending tubular pipe members carried by said base and providing a series of longitudinally spaced 10 vertical air-flow passages, the outer surfaces of said pipe members being spaced apart to provide spaces between said pipe members constituting a series of longitudinally spaced transverse air-flow passages across said base, and a longitudinally extending cap member disposed in spaced relation above and extending between the upper ends of said pipe members and extending downwardly at each side thereof, its lower edges being transversely spaced to provide a continuous open 15 under side in air communication with said transverse air-flow spaces and being substantially below the plane of the upper ends of said pipe members and in spaced parallel relation above said base to define with said base at each side of the ventilator longitudinal air-flow entrance 20 spaces to said transverse air-flow passages, and support means fixing the position of said cap member with respect said pipe members.

2. A ventilator, comprising a base adapted to 30 be mounted over an elongated opening and having a series of longitudinally spaced upwardly extending tubular pipe members carried by said base and providing a series of longitudinally spaced vertical air-flow passages, the outer surfaces of said pipe members being spaced apart to provide spaces between said pipe members constituting a series of longitudinally spaced transverse air-flow 35 passages across said base, and a longitudinally extending cap member disposed in spaced relation above and extending between the upper ends of said pipe members and extending downwardly at each side thereof, its lower edges being transversely spaced to provide a continuous open under side in air communication with said transverse air-flow spaces and being substantially below the plane of the upper ends of said pipe members and in spaced parallel relation above said base to define with said base at each side of the ventilator longitudinal air-flow entrance 40 spaces to said transverse air-flow passages, and the outer side surfaces of said cap member converging downwardly and inwardly toward said longitudinal air-flow entrance spaces.

3. A ventilator, comprising a base adapted to 55 be mounted over an elongated opening, a series of longitudinally spaced tubular pipe members extending upwardly from said base, the outer surfaces of said tubular pipe members above said base being spaced apart to provide transverse air-flow 60 passages between them, a longitudinally extending cap member disposed above said pipe members having a longitudinal opening in its under side in which is engaged the upper ends of said pipe members, the lower edges of said cap member at each side being in parallel upwardly spaced relation to said base, and support means fixing the position of said cap member with respect to said pipe members.

4. A ventilator, comprising a base adapted to 70 be mounted over an elongated opening, a series of longitudinally spaced pipe members extending upwardly from said base, and a longitudinally extending cylindrical cap member disposed above said pipe members having a longitudinal opening in its under side in which is engaged the upper

ends of said pipe members, the lower edges of said cap member at each side being in parallel upwardly spaced relation to said base.

5. A ventilator, comprising a base adapted to be mounted over an elongated opening and having a series of longitudinally spaced upwardly flanged pipe receiving openings, a pipe member engaged upwardly through each of said openings having a flange at its lower end engaging the under side of said base and an external screw thread extending above said base, and a nut engaged with said screw thread bearing upon the upper side of said base and having a tapered recess in its under side engaged by said flange of said opening, and a longitudinally extending cap member disposed above said pipe members and extending downwardly at each side thereof into spaced relation with said base.

6. A ventilator, comprising a base adapted to be mounted over an elongated opening, a series of longitudinally spaced pipe members extending upwardly from said base, a longitudinally extending cap member disposed above said pipe members and extending downwardly at each side thereof into spaced relation with said base, a longitudinally extending damper in said cap member above said pipe members, screw-posts

in certain of said pipe members swivelly connected to said damper, and actuating means connected to said screw-posts for simultaneously rotating them to raise and lower said damper.
